UNITED STATES PATENT OFFICE.

MARK F. BRENNAN, OF SCRANTON, PENNSYLVANIA, ASSIGNOR TO INTERNATIONAL TEXTBOOK COMPANY, OF SCRANTON, PENNSYLVANIA, A CORPORATION OF PENNSYLVANIA.

BOOKMAKING MACHINE.

Application filed November 23, 1927. Serial No. 235,306.

This invention relates to improvements in book-making machines, and more particularly to the palette which is used in placing the filler in cooperative relation with the adhesively applied cover, one object of the invention being the provision of a palette of novel construction which is especially designed to be used in conjunction with the Jacobs book-making machine as shown and described in U. S. Patents Nos. 580,111 and 661,763.

A further object of this invention is the provision of a sectional palette for book-making machines in which yieldingly mounted bars or extensions are provided, two to each section, and so constructed and arranged as to insure the feeding of the fillers to a flexible covering sheet to provide stiff or flexible backs for books, said sections being so constructed and arranged as to render the palette adjustable both longitudinally and transversely to accommodate fillers and covers of different areas.

In the accompanying drawings:—

Figure 1 is a top plan view of the palette, the carrying arm being shown in section.

Figure 2 is an end view of the palette shown in filler-delivering position relatively to the edge folding plungers of the book-making machine, which are here shown in section.

Figure 3 is a section taken on line 3—3 of Figure 1.

Figure 4 is a section taken on line 4—4 of Figure 1.

Figure 5 is a perspective view of two of the presser bars per se with the connecting or extension device attached thereto.

Figure 6 is a perspective view of said connecting or extension device per se.

Figures 7, 8 and 9 are views of the adjustable corners for the yieldingly mounted bars.

Figures 10 and 11 are views of pneumatic means for projecting the bars and forming a yielding pneumatic cushion therefor.

Referring to the drawings, the numeral 10 designates a laterally swinging arm of the book-making machine which has the flanged head 11 for supporting the palette P. F and F' indicate the filler, C the flexible cover sheet, and L the lining strip.

The palette consists primarily of four members 13, 14, 15 and 16, respectively, each one of which is substantially identical in con-

struction, so the description of one will suffice for all. In order to connect the respective sections 13 and 14 and 15 and 16 for longitudinal adjustment, I employ the two bars 17 and 18, one to each pair, the lower edge of the bars being provided with a rib 19 for sliding in the groove 20 of the respective sections so that the bolt 21 with its nut 22 may adjustably attach the sections in their relative positions and in pairs. Each section is provided with a hose-receiving projection 23 and with a rubber vacuum cup as 24, so that the filler and lining strip may be suctionally held in place during the movement from the pile to and upon the cover sheet C. These nozzles 23 are connected by a flexible hose 25 to the main carrying head 10 in the usual manner.

In order to provide a lateral or transverse adjusting means for the respective sections of the palette, the two bars 26 and 27 are connected by means of screw bolts 28 and 28' to the bar 18, while the free ends rest upon the bar 17 and are connected thereto in adjustable relation by means of the bolts 31 which, in turn, clamp the grooved portion 11 of the member 10, as indicated at 29 and 30, to the respective bars 26 and 27. Thus, in this way, the four sections are connected by the respective members 17 and 18 and 26 and 27 to be held in fixed adjusted relation.

Each section has projecting from the upper surface thereof the three lugs 32, 33 and 34. The lug 33 is provided with an opening 35 therethrough which is aligned with the opening 36 of the lug 34, while the lug 32 is provided with an opening 37 therethrough. In this manner, the pin 38 is mounted for limited movement in the openings 35 and 36 and is stopped in its outward movement by means of the screw or bolt 39, the spring 40 being mounted upon the pin and exerting a pressure on the outer face of the lug 33 and cooperating with the spring 42 mounted upon the sliding pin 41 to hold the presser bar 43 outwardly and away from the outer face of its respective section. The lugs 33 and 34 are provided with the openings 44 and 45 which are below and at right angles to the respective openings 35 and 36 and have slidably mounted therein the pins 46 and 47 which are attached to and carry the short presser bar 48, a slotted limiting lug 49 being carried by the bar and cooperating

with the bolt 50 to slidably attach it to the section 13. A spring 46' is mounted upon each of the pins 46 and 47 to hold the presser bar 48 outwardly and away from its section.

5 The vertical ribs 51 and 52 are formed integral with and in spaced relation upon the outer faces of the bars 43 and 48 and provide a means to space the adhesive face of the cover C away from the outer face of the 10 bars so that the adhesive does not adhere to the outer face, thus limiting the surface contacted by the adhesive.

When the sections are adjusted to take the lining strip or back lining section L or 15 are in the position as shown in Figure 1, the space between the respective sections is filled in by the lining strip lifting sections 53 and 54, the same being connected to the under side of the bars 17 and 18, respectively, by 20 means of a screw 55, one to each section. Each section 53-54 is also provided with the suction device 23', which, when in use, is connected to the usual flexible hose connections 25, and thus permits the present palette 25 to simultaneously elevate two fillers F and F' and one lining strip L.

In order that two adjoining bars 43, or two adjoining bars 48 may be made continuous, respectively, there is provided a spring clip 30 or connector 56 which is adapted to be placed either over the upper edges of aligned presser bars or the lower edges as the case may be and the occasion warrant, the said clip 56 being composed of a sheet of flexible 35 spring metal bent upon itself and having a tendency to grip the respective bars upon which it is attached and spanning the same, as illustrated in Figure 5, so as to make a continuous bar so there can be no space between 40 the ends thereof that might permit a pucker or inward fold upon the filler F during the movement of the bars inwardly.

When the present device is in use it is similar to the palettes shown in the various 45 patents to Jacobs, and that to Satenstein, No. 1,328,767, but briefly stated, it is as follows: The flexible cover C is placed upon a spring-pressed bed (not shown) with the usual edge-forming members 60, only one set of which is 50 here shown, in a position to permit the palette with the respective presser bars 43 and 48 fully extended to pass therebetween and place the filler F upon the cover C. When the filler is below the members 60, the members 60 are moved inwardly, engaging the upturned edges of the cover C and pushing them over and upon the upper side of the filler F, and at the same time pushing the respective presser bars against the action of the 55 springs, as is the usual practice, or in a sufficient distance to permit the edge-forming portions 60 to press the up-turned edge downwardly upon the filler F and its inner edge thereof free from the outer edges of the re-

spective presser bars, and then the edge-forming member upon the remaining two sides are moved in to complete the operation. 65

It is evident from the foregoing description that with a palette made according to the present invention a book-making machine is 70 adaptable for use upon the various sized book covers with flexible or stiff fillers and lining strips for the back, and also carrying the lining strip simultaneously with the filler so that when the present palette has completed its 75 operation with the lateral plungers of the book-making machine, the complete book-back, including two fillers with or without the back lining strip, is completed, and is held during the forming operation in a flat non-wrinkled position so as to insure a complete 80 and neat article.

In practice I have found it desirable to provide some means for preventing the puckering of the cover at the corners and at the same 85 time to improve the folded and finished article at this point, and to this end I have employed the construction as illustrated in Figure 7 and in the methods as illustrated in Figures 8 and 9. The bars 43 each have mounted 90 upon one end thereof, the end nearest the corner of the palette, and for limited sliding movement, the spring-actuated compensating bar or extension 65, there being provided the two fixed pins 66 and the slot 67 to insure 95 proper straight-line movement between the parts. The spring 68 is disposed and mounted to hold the extension 65 outwardly with its right-angled head 69 in the desired position for cooperating with the overlapped end of 100 the presser bar 48, as illustrated in the steps in Figures 8 and 9, Figure 8 showing the device in the position it assumes at the initial movement of the palette down between the folding plungers, and Figure 9 when the respective bars 43 and 48 are brought into cooperating position, the extension 65 clearly closing the gap at the corner. 105

In order to provide an alternate for the springs which yieldingly hold the presser bar outwardly, I have shown in Figure 10 a vacuum or suction means, the plunger 69 in this instance being operated upon by a suction or vacuum to hold the presser bar 43 yieldingly outwardly. As shown in Figure 11, pressure 110 is employed instead of suction, and in this instance, the plunger 70 is held outwardly from the pressure at the rear thereof. 115

I claim:

1. A palette for book-cover making machines, including a supporting structure, four sections and two back lining sections, and means for adjustably connecting said sections to the structure to permit the various sections to be adjusted and extend or contract the palette both laterally and longitudinally to accommodate the palette to various areas 120 of covers. 125

2. In a book-cover making machine, a palette composed of four sections transversely and longitudinally adjustable relative to each other, a carrying member to which said sections are adjustably attached, and two yieldingly mounted outwardly pressed bars carried by each section and parallel to the respective outer faces of each section.

3. In a book-cover making machine, a palette composed of four main sections transversely and longitudinally adjustable relative to each other, and arranged in pairs and to provide a transverse space between the two pairs of said sections, a carrying member to which said sections are adjustably attached, two yieldingly mounted presser bars carried by each section and parallel to the respective outer faces of each section, a back lining section for disposition in said transverse space between the two pairs of said main sections and means for connecting said back lining sections to the carrying member.

4. In a book-cover making machine, a palette composed of four main sections transversely and longitudinally adjustable relative to each other and arranged in pairs and to provide a transverse space between the two pairs of said sections, a carrying member to which said sections are adjustably attached, two yieldingly mounted presser bars carried by each section and parallel to the respective outer faces of each section, a back lining section for connection to the carrying member and for disposition in the transverse space between the two pairs of said main sections, and a space filling connection between two alined presser bars.

5. In a book-cover making machine, a palette composed of four sections transversely and longitudinally adjustable relative to each other, a carrying member to which said sections are adjustably attached, a plurality of apertured lugs carried upon the upper face of each section, two pairs of guide pins, one of each pair of which is slidably mounted in one lug and the remaining pins being slidably mounted one in each remaining lug, a presser bar carried by each pair of pins, and a spring mounted upon each pin and bearing against its respective presser bar.

6. In a book-cover making machine, a palette composed of four main sections transversely and longitudinally adjustable relative to each other, a carrying member to which said sections are adjustably attached, three apertured lugs carried upon the upper face of each section, two pairs of guide pins one of each pair of which is slidably mounted in one lug and the remaining pins being slidably mounted one in each remaining lug, a spring mounted upon each pin and bearing against its respective presser bar, a presser bar carried by each pair of pins, and a back

lining section for connection to the carrying member and for disposition between the two pairs of said main sections.

7. In a book-cover making machine, a palette composed of four main sections transversely and longitudinally adjustable relative to each other, a carrying member to which said sections are adjustably attached, three apertured lugs carried upon the upper face of each section, two pairs of guide pins one of each pair of which is slidably mounted in one lug and the remaining pins being slidably mounted one in each remaining lug, a presser bar carried by each pair of pins, a spring mounted upon each pin and bearing against its respective presser bar, a back lining section for connection to the carrying member and for disposition between the two pairs of said main sections, and a space filling connection between two alined presser bars.

8. A section for a book-cover making machine palette having two presser bars, means for yieldingly holding said bars away from the section, and external ribs carried upon the outer face of each presser bar.

9. A palette for book-cover making machines having four sections, each section having three lugs, two presser bars, two pins carrying each bar, one pin of each bar being slidably mounted in one lug and the remaining pins being slidably mounted one in each of the remaining lugs, and a spring mounted on each pin to force its respective bar outwardly.

10. A palette for book-making machines having four sections, each section having three lugs, two presser bars, two pins carrying each bar, one pin of each bar being slidably mounted in one lug and the remaining pins being slidably mounted one in each of the remaining lugs, a spring mounted on each pin to force the respective bar outwardly, and external ribs carried upon the outer face of each presser bar.

11. A palette for book-making machines including four rectangular sections, two bars, one bar adjustably connecting its respective two sections together, two cross-bars adjustably connecting said bars together and the sections for transverse adjustment, and a yielding presser bar carried by and opposed to each external face of each section, two presser bars to each section.

12. A palette for book-making machines including four rectangular sections, two bars, one bar adjustably connecting its respective pair of sections together, two cross-bars adjustably connecting said bars together and the sections for transverse adjustment and to provide a space between said pairs of sections, a yielding presser bar carried by and opposed to each external face of each section, two presser bars to each section, and two adjustable back lining sections connected to

both of the first two bars and disposed in the space between respective pairs of the four sections.

13. A palette for book-making machines including four rectangular sections, two bars, one bar adjustably connecting its respective pair of sections together, two cross-bars adjustably connecting said bars together and the sections for transverse adjustment and to provide a space between said pairs of sections, a yielding presser bar carried by and

opposed to each external face of each section, two presser bars to each section, two adjustable back lining sections connected to both of the first two bars and disposed in the space ¹⁵ between respective pairs of the four sections, and means for making any two of the presser bars continuous.

In testimony whereof I have hereunto set my hand.

MARK F. BRENNAN.
